(57) **CLAIM**

I claim the ornamental design for a rolling storage case, as shown and described.

DESCRIPTION

FIG. 1 is a perspective view of a rolling storage case;

FIG. 2 is a left side elevational view thereof;

FIG. 3 is a right side elevational view thereof;

FIG. 4 is a front elevational view thereof;

FIG. 5 is a back elevational view thereof;

FIG. 6 is a top plan view thereof; and,

FIG. 7 is a bottom plan view thereof.

Broken lines are used to illustrate unclaimed portions of the rolling storage case; broken lines form no part of the claimed design.
